UNITED STATES PATENT OFFICE.

ARTHUR STAFFORD, OF LANCASTER, CANADA.

KNOT FINISHER AND TRIMMER FOR SPOOLING-MACHINES.

SPECIFICATION forming part of Letters Patent No. 650,620, dated May 29, 1900.

Application filed June 6, 1898. Serial No. 682,681. (No model.)

To all whom it may concern:

Be it known that I, ARTHUR STAFFORD, a subject of the Queen of Great Britain, residing at Lancaster, in the county of Glengarry, Province of Ontario, Canada, have invented 5 certain new and useful Improvements in Knot Finishers and Trimmers for Spooling-Frames, &c., of which the following is a specification, reference being had therein to the accompanying drawings.

In the process of winding yarns from spinning-bobbins onto spooler-bobbins and the like frequent piecing or joining of the yarns becomes necessary. This piecing or joining 15 is effected by tying together the ends which are to be united. In the course of a day's labor the attendant upon a spooling-machine or the like is required to tie a great many knots, the number running far into the thousands. After tying and drawing up a knot it is desirable that the loose or free projecting ends of the yarns should be removed, and the duty of effecting the removal of such ends devolves upon the attendant aforesaid. The 20 said removal is effected ordinarily by breaking the loose or projecting ends over the finger or thumb of the attendant close to the knot. Constant repetition of this operation occasions soreness and injury of the finger or 25 thumb which is used for the purpose, with the result that the attendant either fails to break off the ends as closely to the knot as is desirable or shirks the duty altogether and permits the knots, with their loose ends and 30 bunches, to pass onto the spooler-bobbins, thereby giving rise to trouble, breakages, and defective products in the subsequent processes. Various endeavors have been made to 35 obviate the difficulty, as by contriving different kinds of knot tying and trimming devices, and a trimmer has been produced in the shape of a blade on a ring intended to be worn on one finger of the spooler attendant. So far as I am aware, however, no device for the purpose 40 has yet been found sufficiently practical and convenient or satisfactory to come into general use.

The aim of my invention is to provide a simple and convenient device fitted for application to a spooling-frame or the like and whereby to facilitate the operation of trim-

ming or removing the loose or projecting ends at a knot.

The invention consists in the novel device which I now shall proceed to describe with 55 reference to the accompanying drawings. The said device serves not only to assist in removing the loose or projecting ends aforesaid and to cause the disconnection thereof to take place immediately at or adjacent to the knot, 60 but it causes the knot to become fully drawn, tightened, and thus reduced in size, and finished.

Figure 1 of the drawings shows in front elevation a well-known form of spooler-clearer 65 with one form of my invention applied thereto. Fig. 2 is a view thereof in side elevation. Fig. 3 is a view thereof in plan, showing also portion of the supporting-rod of the clearer. Fig. 4 is a perspective showing, detached, the 70 knot trimming and finishing device of Figs. 1, 2, and 3 and illustrating the manner in which a knotted yarn is applied thereto. Fig. 5 is a view in front elevation of a clearer provided with a modification of my invention. 75

In the drawings, 1, Fig. 3, designates a portion of the usual clearer-supporting rod of a yarn-spooling machine, and 2 designates a clearer, the latter being shown mounted upon the said rod in Fig. 3. 80

21 is the upper blade of the clearer. 22 is the lower blade thereof. 23 is the slit between said blades and through which the yarn passes, and 24 is the customary detent for preventing removal of the yarn from the 85 said slit. In the form of clearer which is shown in the drawings each blade is formed with one-half of a bearing, as at 25, which fits the rod 1, and the two half-bearings are clamped upon the said rod to hold the clearer 90 in place by means of screws 240 240.

A device embodying my invention is shown at 3 in Figs. 1, 2, and 3. It here consists of a strip of sheet metal that is bent at its lower end to form a foot 31, the latter resting upon 95 the top of the half-bearing of the upper clearer-blade 21 and having a hole therethrough for the passage of one of the clamping-screws 240, the device being thereby held in place by the said screw. I form the device 100 with jaws, as 32 33, separated by a space, as at 34, Fig. 2, the proximate edges of said

jaws being caused to converge until they almost meet, there being left between the inner portions of said jaws a narrow slit-like opening, as shown, having parallel or substantially-parallel sides along and through which the loose ends projecting from a knot may freely be drawn, the width of this slit-like portion of the opening, however, being such as to prevent the passage of a knot. In the case 10 of the device which is represented in Figs. 1, 2, and 3 I form the jaws and intermediate space by making a slit in the upper part of the sheet-metal strip and bending over one of the tongues which are produced by such 15 slit. (See Figs. 1 and 2.) Good results are secured by making the proximate edges of the jaws somewhat beveled toward the rear side of the device, as at 35 35, since this permits closer approach of the knot to the point 20 at which the disconnection of the loose or projecting ends of yarn is effected.

In the use of the device the ends of yarn requiring to be joined to each other are tied together with a knot in customary manner, 25 and then the yarn, with the knot more or less tightly drawn, is applied to the device in the manner which is illustrated in Fig. 4. The knot being at the rear of the device—that is to say, at the left thereof in Figs. 2 and 4—30 and the loose or projecting ends of yarn extending through the space between the jaws 32 and 33, the said ends are pressed downwardly between the jaws, so as to carry the knot to the narrowest or slit-like portion of 35 the space intervening between the jaws. The said loose or projecting ends are drawn forcibly forward through the slit-like portion of the opening between the jaws, so as to carry the knot into contact with the rear faces of 40 the jaws. The continued pull on the said loose or projecting ends will draw the knot tight and firm and finally will cause said ends to break off at the jaws, close to the knot. Thus the said knot is tightened and completed 45 and also cleared of projecting portions, while by the breaking off of the ends the remainder of the yarn is freed and the winding may be proceeded with. The device is exceedingly convenient to use. All that is required to be 50 done by the operative or attendant is to tie the knot, draw it more or less tightly, throw it over behind the device, passing the loose ends into the space between the jaws, and give

a slight pull downwardly and forwardly on the said ends until the breakage occurs. The latter invariably takes place in front of the knot, closely adjacent to the latter.

In Fig. 5 I have represented my invention as applied to the upper clearer-blade 21, the latter having the upper edge thereof shaped 60 to form the jaws 37 38 and the intervening space 39 terminating in the inner slit-like portion, in which the ends of the yarn take position to facilitate the breaking thereof.

I claim as my invention—

1. A knot finisher and trimmer for spooling-frames, comprising rigid jaws between which the loose or projecting ends of yarn may be passed, said jaws having converging rearwardly-beveled edges, and terminating in 70 a narrow, slit-like opening along which the said projecting ends of yarn may be drawn freely but through which the knots cannot pass.

2. In combination, a yarn guide or clearer for spooling-frames, having suitable clearing-blades between which the yarn runs, and a knot finisher and trimmer for use in disconnecting the loose ends of the yarn and tightening the knot, said finisher and trimmer 80 comprising jaws between which the loose ends of the yarn may be passed by hand, said jaws having converging edges and terminating in a narrow slit-like opening along which the said projecting ends of yarn may be drawn 85 freely but through which the knot cannot pass.

3. In combination, a yarn guide or clearer for spooling-frames, having suitable clearing-blades between which the yarn runs, and a 90 knot finisher and trimmer for severing the loose ends of the yarn and tightening the knot, removably secured to said yarn guide or clearer, said finisher and trimmer comprising jaws between which the loose ends of the yarn 95 may be passed, said jaws having converging edges and terminating in a narrow slit-like opening along which the said projecting ends of yarn may be drawn freely but through which the knot cannot pass.

In testimony whereof I affix my signature in presence of two witnesses.
